BURNISHING MECHANISM

Application filed January 30, 1930. Serial No. 424,638.

This invention relates to burnishing machines and more particularly to machines for burnishing brake bands.

An object of the invention is to provide a burnishing machine in which the burnishing element furnishes the feeding power.

Another object of the invention is to provide a burnishing machine with a feeding element, the driving power of which is furnished by the burnishing element of the machine and a control means for the feeding element.

Another object of the invention is to provide a burnishing machine having an automatic feeding means, the driving power of which is furnished by the burnishing element of the machine and a frictional control means for the feeding means.

A further object of the invention is to provide a burnishing machine having a burnishing disk and a feeding means driven thereby and means associated with the feeding means imposing a drag thereon to prevent the feeding means from moving at the same rate of speed as the burnishing disk.

A still further object of the invention is to provide a burnishing machine which will be simple and inexpensive in construction, highly efficient in use, positive in action, durable in service and a general improvement in the art.

Other objects of the invention will appear from the following description taken in connection with the drawing which forms a part of this specification, and in which:

Figure 1 is a top plan view of a burnishing machine embodying the invention;

Figure 2 is a side elevation partly in section;

Figure 3 is a detailed view illustrating means for locking a brake band on the feeding element; and

Figure 4 is an enlarged detailed view of the feeding means.

Referring to the drawing for more spe-

cific details of the invention, 10 represents a base, having positioned thereon a pedestal 11 supporting a table 12. A motor 13 is bolted or otherwise secured to the table and mounted upon the shaft of the motor is a 50 burnishing disk 14.

As shown, the table is provided with a slot 15 positioned at right angles to the plane of rotation of the disk and preferably in a perpendicular plane passing through the longitudinal axis of the motor shaft. A screw 16 is mounted for rotation on the bottom of the table beneath the slot and is provided with the conventional nut 17 by means of which it may be driven.

A sleeve or block 18 is mounted to travel on the screw 16. This block bears against the bottom of the table on each side of the slot 15. The block has formed integral therewith a stud or shaft 19 which extends upwardly through the slot 15. This shaft supports a sleeve 20 which is secured in position by a nut 21 threaded on the end of the shaft. The sleeve 20 has a flange 22 which bears on the top of the table on each side of the slot and the flange is provided with a pin 23 adapted to engage the slot and retain the sleeve 20 against rotation.

Positioned on the upper face of the flange 22 is a frictional disk 24 and mounted for rotation on the sleeve 20 is a sleeve 25 having a flange 26 engaging the frictional disk 24. The flange 26 has a shoulder periphery in which is secured an annular support 27 by bolts 28. The sleeve 25 is externally threaded 75 to receive an internally threaded sleeve 29. The sleeve 29 is provided with an internal shoulder 30 on which is positioned one race of a ball bearing 31, the other race of which engages the bottom of the nut 21.

The sleeve 29 is provided at its lower end with a cutaway portion 32 in which is positioned a stop 33 to limit the rotary movement of the sleeve. This sleeve is also provided with oppositely disposed lugs 34 to which is 90

secured a plate 35 having lateral projections to which is attached a handle 36. As shown, the lugs 34 and the plate 35 have registering apertures in which bolts 37 are positioned and 5 helical springs 38 are interposed between the lugs 34 and nuts threaded on the ends of the bolts.

The annular support 27 is provided with a shoulder portion 39 and a pin or stud 40, 10 and arranged adjacent to the pin or stud is an eccentric member 41 operated by a lever 42. The eccentric member has attached thereto a hook or fastening member 43, the object of which will hereinafter appear.

15 In operation a brake band is positioned on the annular support with one end engaging the pin 40 and the other end engaging the hook or fastening member 43. The lever 42 is then manipulated to securely clamp and 20 lock the brake band in position. With the brake band thus secured in position, the screw 16 is adjusted to back the brake band hard against the burnishing disk 14 and the sleeve 29 is adjusted through the handle 36 to impose 25 a light initial drag on the support for the brake band through means of the frictional engagement between the disk 26 and the frictional disk 24. With the burnishing disk 14 in motion, the frictional engagement of 30 the burnishing disk with the work piece or brake band will cause the support for the brake band to rotate. It is desired that the support for the band may rotate at a rate of 35 speed less than the rate of rotation of the burnishing disk. This may be readily accomplished by means of the braking or frictional engagement of the support for the work piece with the frictional disk.

40 It will be observed that the burnishing disk furnishes the feeding power for the support 45 through the work piece or brake band and that the rate of rotation of the support and hence the brake band may be readily regulated or controlled by imposing a drag thereon through its frictional engagement with its bearing surface, to either increase or decrease the rate of rotation thereof. It is, of course, understood that it is desirable to impose sufficient drag on the support to cause 50 it to move at a rate of speed less than the rate of rotation of the burnishing disk.

55 While a preferred embodiment of the invention has been described, it is to be understood that this is given merely as an example of the underlying principles of the invention, and since these may be incorporated in other specific mechanical structures, I do not intend to be limited to the structure 60 shown except as such limitations are clearly imposed by the appended claims.

I claim:

1. A burnishing machine comprising a burnishing element, a feeding means positioned for rotation in a plane at right angles to the 65 plane of rotation of the burnishing element

and receiving its driving power from the burnishing element and means imposing a frictional drag on the feeding means.

2. A burnishing means comprising a burnishing element, a feeding means positioned 70 for rotation in a plane at right angles to the plane of rotation of the burnishing element and receiving its driving power from the burnishing element, means for imposing pressure 75 between the burnishing element and the feeding element and means resisting movement of the feeding element.

3. A burnishing machine comprising a burnishing element, a feeding means positioned 80 for rotation in a plane at right angles to the plane of rotation of the burnishing element and receiving its driving power from the burnishing element, means imposing a pressure 85 between the burnishing element and feeding means and means controlling the rate of movement of the feeding means.

4. A burnishing machine comprising a burnishing element, a feeding means positioned 90 for rotation in a plane at right angles to the plane of rotation of the burnishing element and receiving its driving power from the burnishing element, a screw for backing the feeding means against the burnishing element and means including a frictional element and a screw for imposing a drag on the 95 feeding element.

5. In a burnishing machine for cylindrical surfaces, a plane burnishing surface, means for rotating the burnishing surface in 100 its own plane, a rotatable work support designed to maintain the burnishing surface and the cylindrical surface in tangential relation and adapted to be frictionally driven by the rotation of the burnishing surface, and frictional means imposing a drag on the 105 work support.

In testimony whereof, I have hereunto signed my name.

ROBERT J. STATZ.
